UNITED STATES PATENT OFFICE.

J. D. ALVORD, OF BRIDGEPORT, CONNECTICUT.

IMPROVEMENT IN MAKING EMERY-WHEELS.

Specification forming part of Letters Patent No. 30,189, dated October 2, 1860.

To all whom it may concern:

Be it known that I, J. D. ALVORD, of Bridgeport, in the county of Fairfield and State of Connecticut, have invented a certain new and useful Method of Making Emery-Wheels; and I do hereby declare that the following is a full, clear, and exact description of the same, reference being had to the accompanying drawings, forming a part of this specification, in which—

Figure 1 represents a front elevation of my invention. Fig. 2 is a central section of the same.

Similar letters of reference in both views indicate corresponding parts.

The usual method of constructing emery-wheels has been to press or cast the plastic mass of which the wheel is to be composed around a central tube having a smooth surface, which serves to receive the arbor or mandrel upon which the wheel is to rotate when in use. The contraction of the plastic material by drying is such as to hold or fasten the wheel upon the tube. As an additional means of securing the wheel to the tube it has been customary to place disks of metal over the extremities of the tube after the wheel has become dried, these disks constituting flanges between which the wheel is pressed by screwing or riveting the disks upon the tubes; but this mode of construction has proved defective, because the disks when applied after the wheel is dried cannot be made to hold the wheel with sufficient firmness to prevent it from becoming loose from the tube and thus useless, and if the wheels are used without the flanges they are still more weak at their junction with the tube. Another serious disadvantage of the present method of manufacture is that the portion of the wheel next the tube is liable to crack for want of lateral support when the material composing the wheel shrinks in drying upon the tube, and by this cracking the wheel is rendered weak and useless.

The nature of my improvement consists in pressing or casting the wheel upon a flanged tube, so that when the wheel contracts in drying the central part thereof will have lateral support, and thus be prevented from cracking, and so that the wheel will by contraction

become firmly attached to the tube and flanges, all as hereinafter represented and described.

To enable those skilled in the art to make and use my improvement, I will proceed to describe its construction and operation, reference being had to the accompanying drawings, forming a part of this specification.

A represents the emery-wheel composed of ground emery intermingled with a solution of glue, gum, or other binding substance, in such proportions that when the mass solidifies by drying it will be hard and stone-like, and thus suitable for grinding and polishing purposes. The mass of which the wheel is to be composed is while in a plastic condition placed in a mold of circular form and then pressed so as to be shaped into the intended wheel. The tube B, composed of brass or other metal, may be first placed in the mold with one of the flanges attached, and the material pressed or cast around it, the other flange being afterward placed upon the extremity of the tube and embedded into the soft material; or, what is precisely equivalent, the wheel may be first pressed into the required state, and while yet soft and green the tube B may be forced through its center, and the two flanges placed upon the extremities of the tube and embedded in the plastic material, so that the outer edges of the flanges will be flush with the sides of the wheel, as shown in Fig. 2. The ends of the tube are now riveted over upon the flanges, and the operation is complete. When the wheel has become thoroughly dry, it will be found to have shrunk or contracted with great force upon the tube and flanges without any cracking, owing to the lateral support given by the flanges to the central part of the wheel during the drying process.

By reference to Fig. 2 it will be observed that the flanges are curved or corrugated in form. I prefer to fashion them in this manner instead of using straight-sided flanges, because by such corrugation or curving the surface of metal is increased upon which the wheel may shrink, and thus greater strength of attachment between the wheel, tube, and flanges is obtained.

Having thus described my invention, what

I now claim as new, and desire to secure by Letters Patent, is—

The method herein described of making emery-wheels, and which consists in pressing or casting the wheel upon a flanged tube, so that when the wheel contracts in drying the central part thereof will have lateral support and thus be prevented from cracking, and so

that the wheel will become firmly attached to the tube and flanges, all as herein represented and described.

J. D. ALVORD.
